(57) **CLAIM**

The ornamental design for a portable water filter, as shown and described.

DESCRIPTION

FIG. 1 is a perspective view, as viewed from above, of a portable water filter showing my new design;

FIG. 2 is another perspective view thereof, as viewed from below;

FIG. 3 is a side elevation view thereof, the opposite side elevation view being a mirror image thereof;

FIG. 4 is a rear elevation view thereof;

FIG. 5 is a front view thereof;

FIG. 6 is a top view thereof;

FIG. 7 is a bottom view thereof;

FIG. 8 is another perspective view thereof, as viewed from above, showing the filtration chamber in an extended position;

FIG. 9 is a perspective view, as viewed from above, of another embodiment of my new design;

FIG. 10 is another perspective view thereof, as viewed from below;

FIG. 11 is a side elevation view thereof, the opposite side elevation view being a mirror image thereof;

FIG. 12 is a rear elevation view thereof;

FIG. 13 is a front view thereof;

FIG. 14 is a top view thereof;

FIG. 15 bottom view thereof; and,

FIG. 16 is another perspective view thereof, as viewed from above, showing the filtration chamber in an extended position.

The broken lines in the drawings are for purposes of illustrating portions of the portable water filter that form no part of the claimed design.

1 Claim, 6 Drawing Sheets
